(57) **CLAIM**

The ornamental design for a patient monitoring device with graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the U.S. Patent and Trademark Office patent file or records, but reserves all other copyrights whatsoever.

The single FIGURE is a front view of a patient monitoring device with a graphical user interface.

The broken line showing of the patient monitoring device is included for the purpose of illustrating the unclaimed environment of the graphical user interface and forms no part of the claimed design. The broken lines illustrating the unclaimed portions of the graphical user interface form no part of the claimed design.
